PIERRE R. FALK, OF NEW YORK, N. Y.

AIR CIRCULATING AND HEATING APPARATUS.

Application filed November 22, 1926. Serial No. 150,109.

This invention relates to apparatus for circulating heated air and has particular reference to an apparatus which may be employed in cold weather as a heater and in 5 warm weather for promoting the circulation of air in a room to cool the same.

More specifically the invention comprehends a water-heated radiator in which water is heated and circulated by an electric 10 heater and through which the air in a room is circulated to raise the temperature in the room to the proper degree.

The invention further comprehends in an apparatus of the character set forth, means 15 for rendering the radiator unit inactive whereby the device may be employed for promoting circulation of the air in a room to agitate and cool the same.

The invention furthermore comprehends 20 an apparatus of the character set forth which is comparatively simple in its construction, inexpensive to produce, economical to operate and which is highly efficient in its purpose.

25 With the above recited and other objects in view, reference is had to the following specification and accompanying drawings in which there is exhibited one example or embodiment of the invention which is in no 30 way intended as a limitation upon the scope of the appended claims as it is to be clearly understood that variations and modifications which properly fall within the scope of said claims may be resorted to when found expedient.

In the drawings—

Figure 1 is a sectional view taken approximately on the line A—A of Fig. 2;

40 Fig. 2 is a side view with parts in section.

Referring to the drawings by characters of reference, the device preferably includes a casing 10 having inlet ports 11 and a radiator unit 12 defining outlet openings 13. 45 The radiator unit comprises a hollow body 14 through which air tubes 15 extend, said tubes defining the outlet openings 13. From a point adjacent its lower end, a water circulation pipe 16 extends upwardly to a 50 point adjacent the top wall 17, the lower end of the pipe 16 having a flared or enlarged intake 18 arranged over a well 19 and provided with a valve 20. An electric resistance heater 21 of any approved type is 55 disposed immediately below the well for heating the water to cause an upward circu-

lation of the same through the pipe 16 from whence it gravitates downwardly around the air tubes 15 to the bottom of the radiator unit. Within the casing 10, a device such as an electric fan 22 is mounted for drawing air through the inlet ports 11 and expelling the same through the air pipes 15 or outlet openings 13. The heat radiated from the heated water in the radiator unit serves to 60 heat the air expelled through the outlet openings or air pipes 15 so that within a short length of time the temperature in the room in which the apparatus is arranged will be raised to the proper degree. The 65 heating element and the fan are preferably arranged in parallel in a circuit 23 which includes a source of supply 24 and the conductors 25 which lead to the electric heater 21 have included therein a detachable plug 70 element 26 which allows for the disconnection of the heater from its source of supply when it is desired to use the apparatus as an air circulating or agitating means only. In order to render the device safe, the radiator 75 unit is provided with a safety valve 27 which is connected with a circuit breaker 28 in the circuit 23 for cutting off the electric heater 21 in event of an excessive heating of the water in the radiator unit either by virtue of failure of the fan to operate or for 80 any other cause.

From the foregoing it will be seen that the present invention embodies an electrically operated means for radiating heat and for circulating air through the heat generated in the radiating means so as to heat the air for insuring a rise in temperature.

It is obvious that the device may include a thermostatic control, if desired, for automatically rendering the same active and inactive in accordance with the temperature desired.

What is claimed is:

1. An apparatus for circulating and heating air, including a casing having air inlet and outlet ports, means within the casing for drawing in air through the inlet and expelling the same through the outlet ports, and an electrically heated closed water radiator through which the heated water is circulated, having air passages therethrough, mounted in the outlet for radiating the heat to heat the air during its expulsion.
2. An apparatus for circulating and heating air including a casing having air inlet and outlet ports, means within the casing

- 2
- for drawing in air through the inlet and expelling the same through the outlet ports, an electrically heated closed water radiator through which the heated water is circulated, having air passages therethrough, mounted in the outlet for radiating heat to heat the air during its expulsion, and means for rendering the heat-radiating means inactive or to adapt the device as an air circulating means only.
3. In an apparatus for effecting the circulation of air and heating thereof, a casing having inlet and outlet ports, a water-heated radiator framing the outlet, electrical means for heating and circulating the water in the radiator, and an electrically operated circulating means within the casing for drawing in the air through the inlet and expelling the same through the outlet ports.
4. In an apparatus for effecting the circulation of air and heating thereof, a casing having inlet and outlet ports, a water-heated radiator framing the outlet, electrical means for heating and circulating the water in the radiator, and an electrically operated circulating means within the casing for drawing in the air through the inlet and expelling the same through the outlet ports, a safety valve provided in the radiator, and means operated thereby for breaking the circuit of the electric heating means.

PIERRE R. FALK.
